UNITED STATES PATENT OFFICE.

ARCHIBALD EDWARD WILSON, OF ELKHORN, CANADA.

FREEZING-BOX.

SPECIFICATION forming part of Letters Patent No. 743,126, dated November 3, 1903.

Application filed May 21, 1903. Serial No. 158,166. (No model.)

To all whom it may concern:

Be it known that I, ARCHIBALD EDWARD WILSON, a subject of the King of Great Britain, residing at Elkhorn, in the county of 5 Dennis, in the Province of Manitoba, Canada, have invented certain new and useful Improvements in Freezing-Boxes; and I do hereby declare that the following is a full, clear, and exact description of the invention, such 10 as will enable others skilled in the art to which it appertains to make and use the same.

In some parts of the country where a scarcity of water exists no opportunity is afforded 15 during the winter season for gathering natural ice from rivers and lakes and for this reason ice is expensive and difficult to obtain in these districts. These observations apply especially to rural districts having primitive 20 transportation facilities. While the facilities for the production of natural ice in these localities are meager and wholly insufficient 25 to meet the demands, the facilities for packing and storing ice are exceptionally good, as the large quantity of straw useful in packing ice is easily to be had.

The object of this invention is to provide 30 a receptacle which is especially adapted for use in the localities mentioned, which receptacle is intended to be filled with pure water repeatedly during the winter season and placed in an exposed position, so that the 35 water contained therein may freeze. The receptacle is constructed in such a manner that it adapts itself to the expanded condition of the water in its solid state, in this manner preventing any possible injury to the receptacle and enabling it to be used again and again for the purpose suggested.

In its general construction the invention 40 consists of a box formed with expandable joints and suitable arrangements for insuring that the box will be water-tight.

The invention consists in the construction 45 and combination of parts to be more fully described hereinafter and definitely set forth in the claims.

In the drawings which fully illustrate my 50 invention, Figure 1 is an end elevation of the box. Fig. 2 is a side elevation. Fig. 3 is a vertical section of the box, taken substantially on the line 3 3 of Fig. 1. Fig. 4 is a horizontal section taken substantially on the line

4 4 of Fig. 1. Fig. 5 is a perspective. Fig. 6 is a perspective of a part used in connection with the box to insure its being water-tight. 55

Throughout the drawings and specification the same numerals of reference denote like parts.

Referring more particularly to the parts, 1 represents the receptacle mentioned above, 60 which consists, preferably, of a substantially square box comprising sides 2 and ends 3, which are formed of stout material. It should be observed that these sides and ends connect with each other at their extremities in 65 mortised or rabbeted points 4, and, as indicated most clearly in Fig. 3, upon their inner faces the vertical walls of the box are provided below with longitudinally-disposed grooves or recesses 5, which grooves receive 70 the laterally-projecting tongues or flanges 6, which flanges project from the edges of a substantial bottom 7.

It should be understood that while the parts of the box are assembled in the manner indicated they are not permanently secured together at the joints, but are simply constrained into their proper position. To this end near the corners of the box are provided springs 8, preferably of helical form, as 80 shown, there being preferably two of these springs located at each corner and disposed, respectively, near the upper and lower edges of the wall. These springs are attached at 9 to the wall of the box, and their free extremities 85 10 are attached to straps 11, which are preferably formed of leather and which pass around the corners of the box in the manner shown, these straps being provided near their opposite extremities with elongated slits or openings 12, through which slits pass fasteners, such as the screws 13, which attach in the wall of the box at these points. From this arrangement it should be evident that while the side walls of the box are constrained together 95 this constraint could be readily overcome by a force acting outwardly from within the box in such a manner as to push out the walls and expand or enlarge the interior or capacity of the box. 100

It should be observed that the vertical corners or edges of the box are rounded upon their outer sides, as indicated at 14, so as to facilitate the slipping of the straps 11 upon

the material of the box, as they necessarily will slip as the box expands. Within the interior of the box I place a water-tight receptacle or lining 15, which is preferably of the 5 form shown in Fig. 6, being of rectangular or box-like form of substantially the dimensions of the interior of the box. This receptacle is preferably formed of some light inexpensive material, such as paper that has been treated 10 with paraffin to render it waterproof, or other material having similar properties may be used for the purpose.

After the inner receptacle 15 has been set within the box, as suggested, it is filled with 15 water and placed in an exposed position, so as to allow the water to freeze. In freezing of course the solidification of the water produces the lateral expansion, which is compensated for by the possible movement of the side 20 walls of the box, and hence no injury is done to the box, which consequently may be filled with water again and again for the same purpose.

The material out of which the box is constructed is preferably hard wood, and it is expected that the box would be made of any dimensions desired, so as to adapt it to the peculiar requirements or necessities of those 25 to whom it would be useful.

It should be understood that the material 30 out of which the inner receptacle 15 is formed would be inexpensive, so that if destroyed by the expansion of the water it could be easily replaced, and it should be borne in mind that 35 while this inner receptacle is of this delicate, destructible, or waterproof material the outer receptacle operates to support the walls of the same, so as to enable them to withstand the very appreciable pressure and distorting effects 40 due to the pressure of the water which would be maintained within the inner receptacle.

While I have shown in the accompanying drawings the preferred form of my invention, it will be understood that I do not limit myself to the precise form shown, for many of the 45 details may be changed in form or position without affecting the operativeness or utility of my invention, and I therefore reserve the

right to make such modifications as are included within the scope of the following 50 claims or of mechanical equivalents to the structure set forth.

Having described my invention, what I claim, and desire to secure by Letters Patent, is—

1. A receptacle, comprising vertical walls and a bottom, said walls being jointed together, and jointed to said bottom, springs disposed at the vertical corners of said receptacle, flexible straps attached to said springs, 60 and passing around said corners, said straps having slits therethrough, and fasteners passing through said slits, and carried by said vertical walls.

2. A receptacle, the walls whereof are jointed together, there being rounded corners adjacent to said joints, flexible straps passing around said corners and attached to said walls, and springs attached to said straps, and adapted to constrain said receptacle into contracted form.

3. A receptacle having a bottom with a laterally-projecting tongue extending about the edge thereof, side walls having longitudinally-disposed horizontal grooves adapted 75 to receive said tongue, said side walls having rabbeted joints therebetween, a pair of opposite members of said side walls having rounded corners, removable flexible straps having slits therein passing around said corners, and disposed adjacent to the upper and lower portion of said receptacle, fastening devices mounted in the walls of said receptacle, and passing through said slits, springs attaching to the extremities of said straps, 85 and adapted to constrain said side walls inwardly, and a water-tight lining formed of paraffin-paper disposed within said receptacle, and conforming to the interior thereof.

In witness whereof I have hereunto set my 90 hand in the presence of two witnesses.

ARCHIBALD EDWARD WILSON.
